(57) **CLAIM**

The ornamental design for a guide for lens cover, as shown and described.

DESCRIPTION

This application is related to U.S. application Ser. No. 29/591,558, filed Jan. 20, 2017.

FIG. 1 is a top perspective view of a guide for a lens cover; FIG. 2 is a top view of the guide for a lens cover of FIG. 1; FIG. 3 is a bottom view of the guide for a lens cover of FIG. 1;

FIG. 4 is a view of the left side of the guide for a lens cover of FIG. 1;

FIG. 5 is a view of the right side of the guide for a lens cover of FIG. 1;

FIG. 6 is a rear view of the guide for a lens cover of FIG. 1;

FIG. 7 is a front view of the guide for a lens cover of FIG. 1; and,

FIG. 8 is a perspective view of the guide for a lens cover of FIG. 1 shown mounted on a goggle strap adjacent the lens cover, the broken lines depicting environmental subject matter only and forming no part of the claimed design.

1 Claim, 3 Drawing Sheets
